UNITED STATES PATENT OFFICE.

WILLIAM C. YOUNG, OF FONTANA, KANSAS.

AIRSHIP.

1,128,648.

Specification of Letters Patent Patented Feb. 16, 1915.

Application filed April 17, 1913. Serial No. 761,734.

To all whom it may concern:

Be it known that I, WILLIAM C. YOUNG, a citizen of the United States, residing at Fontana, in the county of Miami and State of Kansas, have invented certain new and useful Improvements in Airships, of which the following is a specification.

This invention relates to air ships, particularly to those of a dirigible type, and has for its object the provision of a device of this character which may be collapsed to form a species of aeroplane.

Another object is to provide a device of this character formed upon and supported by an improved form of frame work which is adapted to serve as a container for gas lighter than air.

A further object is the provision of an improved construction of frame work tubing.

Other objects and advantages such as durability and the general improvement of the art will be brought out fully in the following specification and illustrated in the accompanying drawings in which—

Figure 1 is a side elevation of my complete air ship, Fig. 2 is a front elevation thereof, Fig. 3 is a cross sectional view thereof showing the machine in its collapsed position, Fig. 4 is a top view with parts broken away to more clearly illustrate the construction, Fig. 5 is a longitudinal sectional view through one of the frame work tubes and Fig. 6 is a longitudinal sectional view through one of the frame work tubes showing a modified form.

Referring more particularly to the drawings 1 designates the gas bag of the machine as a whole, which comprises the rectangular portion 2 and the cylindrical portion 3. The rectangular portion 2 comprises the bottom 4, side walls 5, end walls 6 and the top wall 7, supported and braced by the bars 8 and 8^a which are connected with the frame work to be described. The cylindrical portion 3 comprises a pair of longitudinally disposed shells 9 preferably crescent-shaped in cross section and which are supported by curved bars 10 which extend around the outside of each shell. The bars are pivotally connected at their upper ends with a horizontal longitudinally extending plate 11 as shown at 12, and are also pivotally connected at their lower ends with the horizontal bars 8, as shown at 13. The frame work of the machine comprises an upper frame which is composed of a plu-

rality of tubular members 14 which extend longitudinally and are connected at their ends by curved sections 15. The gas bag previously described is connected with this frame work in any desired manner, but for purposes of illustration I have shown the vertical bars 8 as connected with collars 16 surrounding the outermost tubular members 14. Supported from the upper frame by means of vertical hangers 17, is a sub-frame which comprises a pair of parallel longitudinally extending tubular members 18 connected at their ends by curved sections 19. A platform 20 is disposed upon the members 18 and secured thereto in any desired manner. This platform is adapted to support the engines.

Connected with the tubular members 18 are hangers 21 through the lower ends of which are journaled short shafts 22 formed upon the extremities of hollow propeller shafts 23. A plurality of propellers 24 are secured upon the shafts 23. Secured upon the ends of the short shafts 23 are bevel pinions 25 which are adapted to mesh with other bevel pinions 26 secured upon transverse shafts 27 supported by brackets 28 formed on the hangers 21. Upon each of the shafts 27 is secured a fly wheel 29.

Secured upon the platform 20 adjacent its forward edge is a windlass 30 about which is trained a cable 31 which extends outwardly of the hangers 17 upon which it is guided by pulleys 32. The cable 31 extends rearwardly of the machine and is connected with the ends of a transverse bar 33 which extends through a rudder 34 which is pivotally mounted in brackets 35 secured upon the rear portion of the frame work. Seats 36 are also supported upon the platform 20 as shown and are preferably formed hollow and filled with gas which is lighter than air.

Engines 36 and 37 are disposed upon the platform 20 and are provided upon their shafts with pulleys 38 about which are trained belts 39 which extend downwardly and around pulleys secured upon the hollow shafts 23. Adjacent the engine 37 is secured a reel 40 which may be connected with the engine 37 by means of a shifting lever 41 which throws clutch members into engagement with each other. The purpose of this reel will be described later.

In order to collapse the gas bag from the position shown in Fig. 2 to the position shown in Fig. 3 I provide the windlass 42

secured upon the platform 20 adjacent the engine 36, and adapted to be connected therewith by means of clutch members and a shifting lever 43. A cable 44 is trained about the windlass 42 and extends over guide pulleys 45 secured outwardly of the tubular members 14, and is connected with the horizontal bars 8^a which support the portion 2 of the gas bag.

10 The operation of the machine is as follows: Assuming that the various portions of the gas bag have been filled with gas ready for starting, and that the machine is held down by cables attached to any desired portion 15 of the frame work; in order to rise, it is merely necessary to disengage the cables, whereupon the lifting power of the gas bag will immediately cause the machine to rise. After the desired altitude has been reached 20 further ascent of the machine can be prevented by starting the engine 36 and shifting the lever 43 so that the windlass 42 will be rotated. The cable 44 will then pull downwardly and outwardly upon the horizontal bars 8^a thus causing the rectangular portion 2 of the gas bag to discharge a portion 25 of the gas contained therein out through valve structures 46 which are so constructed that they will not open unless pressure within 30 in the rectangular portion 2 has been greatly increased by the collapsing of the rectangular portion 2. As soon as sufficient gas has been allowed to escape and the machine remains at the same altitude, the lever 43 may 35 be shifted to stop the motion of the windlass 42. The engines 36 and 37 will then rotate the shafts 23 causing the propellers 24 to propel the ship in a horizontal direction, and the side walls 5 of the portion 2 40 and the bottom wall of the compartment serve as soaring planes to a greater or less extent. It will be noted that the ship may be easily guided by means of the windlass 30 connected with the rudder 34. As the shafts 45 23 rotate, the fly wheels 29 will also rotate by virtue of the intermeshing of the pinions 25 and 26. These fly wheels steady the motion of the machine and exert powerful opposition to any lateral oscillation of the 50 machine. When the desired destination has been reached and it is desired to make a landing, which would probably be made at a special station designed for the purpose, the engines are slowed down or reversed, as 55 required, to bring the machine directly over the station. One of the crew may then be lowered from the machine by means of a breeches-buoy secured to the end of the cable passing from the reel 40. This member of 60 the crew would then attach the end of the cable to something firmly attached upon the ground and the ship may then be pulled down by winding the reel 40.

In order to make the frame work of the 65 machine as light as possible I prefer to em-

ploy a tubular frame construction as shown in Fig. 5 or Fig. 6. These tubular members comprise hollow cylinders 47 open at their ends and provided at their centers with an inwardly opening check valve 48.

70 Pistons 49 fitting snugly within the cylinder 47 are disposed adjacent and on either side of the valve 48. It will be readily seen that when gas is forced into the cylinder 47 the pistons 49 will be forced outwardly toward the ends of the cylinder 47 and will be retained by the inturned flanges 50. The cylinder 47 will thus be filled with gas.

75 In Fig. 6 a slightly modified form of the tube is shown. In this form a cylinder 51 is open at one end where it is provided with an inturned flange 52, and is closed at the other end where it is provided with an inwardly opening check valve 53. A piston 54 is disposed within the cylinder 51 and 80 adjacent its closed end, so that when gas is introduced through the valve 53 the piston 54 will be moved longitudinally of the cylinder forcing out the air contained therein.

85 It will be understood that various changes 90 in the form, construction, and arrangement of parts may be resorted to without departing from the spirit of the invention or limiting the scope of the subjoined claims.

Having thus described my invention, 95 what I claim is:—

1. In an airship, a frame comprising a plurality of tubes adapted to contain gas, each of said tubes comprising a cylindrical shell having its ends open and provided 100 with inwardly extending flanges, an inlet pipe communicating with said shell intermediate its ends, a check valve in said inlet pipe, and a pair of pistons disposed within said shell at each side of said inlet pipe and 105 movable toward the ends of the shell when gas is admitted through said inlet pipe, whereby the air will be forced from the shell by said pistons, the final engagement of said pistons with said flanges forming 110 the end closures for said shell.

2. In an air ship, a frame, vertical uprights pivoted upon said frame, substantially horizontal rods pivoted upon said uprights, a flexible gas bag connected and retained in position by said uprights and said rods, and means for pulling the upper ends of said uprights outwardly, whereby said gas bag may be collapsed, the sides of said bag disposed against said uprights then 115 serving as planes, said gas bag being provided with outlet openings provided with valves openable by the increased pressure within said gas bag caused by such collapsing.

3. In an airship, a frame, uprights pivoted thereto, substantially horizontal rods pivoted upon said uprights, a flexible gas bag retained by and connected with said uprights and said rods, means for pulling 120

the upper ends of said uprights outwardly for partially collapsing said gas bag, the sides of said bag then serving as planes, curved rods pivoted upon the inner ends of 5 said substantially horizontal rods, a plate connecting the upper ends of said curved rods, and a pair of gas bags disposed within the closure formed by said curved rods, the lower ends of said curved rods being moved 10 outwardly by the outward movement of said

uprights, whereby said curved plate and said last named gas bags will serve as auxiliary planes.

In testimony whereof I affix my signature in presence of two witnesses.

WILLIAM C. YOUNG.
